Primary Examiner — Jae Liang*Assistant Examiner* — Christopher Torma(74) *Attorney, Agent, or Firm* — Economou IP Law; Vangelis Economou(57) **CLAIM**

The ornamental design for a nine drawer service cart as shown and described.

DESCRIPTION

FIG. 1 is a perspective view of a nine drawer service cart with an open top showing my new design; FIG. 2 is a perspective view of the nine drawer service cart of FIG. 1 showing the cart with a closed top; FIG. 3 is a front elevational view of the service cart shown in FIG. 2; FIG. 4 is a back elevational view thereof; FIG. 5 is a right side view thereof; FIG. 6 is a left side view thereof; FIG. 7 is a top view thereof; and, FIG. 8 is a bottom view thereof. The broken lines in the drawings illustrate portions of the nine drawer service cart that form no part of the claimed design.
